BARBED WIRE REEL HOLDER

Barney F. Wiggins, Rte. 1, Box 174, Livingston, Tex.
Filed Aug. 12, 1959, Ser. No. 833,343
1 Claim. (Cl. 242—86.64)

The present invention relates to a new and improved device for reeling barbed wire.

Barbed wire used in constructing fences is customarily sold in reels in various uniform or standard sizes. As is well known, a barbed wire fence is comprised of a plurality of posts, usually of wood and most frequently of cedar, placed in predetermined locations on the line the fence is to follow and two or more strands of barbed wire are affixed perpendicularly to the posts, usually by stapling, and parallel to each other. The number of strands used normally varies with the height of the fence.

Because of the very nature of barbed wire, i.e., with its protruding barbs, it is difficult to run a strand of wire on fence posts or the like, and is even more difficult to get the strands tightly between the posts. In manually stringing and tightening the wire injury to the person from the barbs quite frequently results.

Machines currently being used for overcoming the aforementioned difficulties are expensive and beyond the economical reach of the average person stringing barbed wire fences.

It is therefore an important object of the present invention to provide a new and improved device for use in stringing barbed wire fences which is inexpensive and can readily and easily be used by one or two persons.

Another object of the present invention is to provide a new and improved means for holding and reeling a reel of barbed wire.

Another important object of the present invention is to provide a new and improved means for quickly and easily applying tension to a strand of barbed wire being used in stringing a fence.

Still another object of the present invention is to provide a new and improved means for holding and carrying reels of barbed wire including a portable container or basket which may be readily attached thereto or detached therefrom.

The construction designed to carry out the invention will be hereinafter described, together with other features thereof.

The invention will be more readily understood from a reading of the following specification and by reference to the accompanying drawings forming a part thereof, wherein an example of the invention is shown, and wherein:

FIG. 1 is a side elevation of the device of the present invention with a reel of barbed wire positioned thereon and in rotatable position;

FIG. 2 is a side elevation similar to FIG. 1 but illustrates the brake of the present invention in position so as to lock the reel of barbed wire and the wheels together;

FIG. 3 is a view partly in section and partly in elevation illustrating the details of the method for connecting the wheels, axle and handle together;

FIG. 4 is an isometric view, partly in section and partly in elevation, illustrating the details of the means used to lock the rest arm or handle support means in an active position.

The device of the present invention is generally indicated at 10 in FIG. 1, and as seen in the drawings comprises a pair of wheels 12, an axle 14, a handle 16 connected to the axle 14, a brake rod 18 slidably positioned on the handle 16, and a portable container 15 which may be positioned on the axle 14.

2

The handle 16 is illustrated as being constructed of two identical rods or bars 16' and 16" positioned adjacent each other and connected together by any suitable means such as welding or the like. At one end of each of the handle portions 16' and 16" is a right angle bend 16a which forms the handle portions 16b for gripping by the hand of an operator. The opposite ends of the rods 16' and 16" are flared outwardly from each other at 16c so that the rod portions 16d form a V. The rods 16' and 16" are bent inwardly at 16e forming the rod portions 16f which are parallel to each other. The ends of the rod portions 16f are bent slightly outwardly and then inwardly, approximately forming a hook 16g (see FIG. 3) with the end portions 16h thereof extending into each end of the axle 14.

The resiliency of the handle rods 16' and 16" of the handle 16 enables the end or hook portions 16g to be flexed from each other to be either inserted in or withdrawn from the axle 14.

Such resiliency or tension in the rods 16' and 16" tends to force the end portions 16g toward each other thereby holding the handle 16 in the axle 14. A lock pin 22 is positioned in a hole or opening 14a in the axle 14, outwardly of each of the wheels 12 and inwardly of the handle ends 16h, thereby locking the wheels on the axle 14. After the handle ends 16h are withdrawn from the axle 14 the pin 22 may be readily removed thus permitting the wheels 12 to be removed from the axle 14.

Referring to FIG. 3 the details of connecting the wheels to the axle can be more easily seen. In the center of each of the wheels 12 is an opening 12a which is of a larger diameter than the axle 14 thus permitting the axle 14 to be positioned and extend through the openings 12a of the wheels 12. On each end of the axle 14 are a plurality of holes 14a, 14a' and 14a'', as illustrated in FIG. 3, extending through the axle 14 and adapted to receive a pin or cotter key 22 or other suitable means for retaining the wheels 12 on axle 14. The plurality of holes 14a, 14a' and 14a'' permits the space between the wheels 12 to be varied as desired.

The wheels 12 are illustrated as being of one piece or body but have a circumferential flange 12b formed thereon for contact with the earth or ground 8. They may be provided with rubber tires if desired.

The rod which functions as a brake means extends longitudinally on the handle 16 and as shown in the drawings is carried on top of the handle portion 16' and 16" respectively. The rod 18 has a pointed or sharpened end 18a and on the opposite end a right angle bend 18b is formed which defines the portion 18c to be gripped by the hand of the operator. A pair of brackets 26 are positioned on the handle 16 so as to receive the rod 18 therethrough and accommodate longitudinal and rotational movement of the rod 18 on handle 16 when the rod is moved to engage the barbed wire as shown in FIG. 2, or when the rod 18 is moved to disengaged position as shown in FIG. 1. The upper bracket 26' may also serve as a stop for the rod handle portion 18c.

A handle support or rest arm 28 is attached to the underside of the handle 16 by means of a hinge 30 suitably attached to the handle at 16''' and to the rest arm 28 at 28'. When the rest arm 28 is not in use it may be attached at its lower end 28'' to a clip or clamp 34 which is illustrated in detail in FIG. 4. Such clamp 34 is positioned on the handle 16 and is of such configuration and construction as to snap into place on the handle. Clamp arms 34' and 34'' are under tension so as to urge them together. Thus when the rest arm 28 is placed between the clip arms 34' and 34'' the rest arm 28 is held in position adjacent the handle 16.

The device of the present invention is particularly adapted to the use of one or two individuals engaged in

stringing barbed wire fence. In the use of the invention the handle 16 is disconnected from the axle 14 by removing the end portions 16h of the handle 16 from the axle 14. The pin or key 22 is removed from the axle 14 and one of the wheels 12 is then removed thus permitting a reel of barbed wire to be placed on the axle 14. The wheel 12 is then replaced on the axle 14, the pin 22 is positioned in the hole 14a of the axle 14 and the handle 16 is attached to the axle 14. The wheels 12 are of a larger diameter than the external diameter of the barbed wire reel (not seen) thus preventing any friction between the ground 8 and the barbed wire reel.

As can best be seen in FIG. 1 of the drawings, the outermost end 36 of the barbed wire reel is pulled out so as to be attached to a fence post in a manner well known in the art. The device 10 is then pulled away from the place of the barbed wire connection on the fence post and since the reel carried by the axle 14 rotates thereon and with the wheel 12, the barbed wire is unreeled. This pulling is normally done by hand.

The wheels 12 thus rotate in a counterclockwise direction and the barbed wire reel also rotates in a counterclockwise direction. When it is desired to tighten the strand 36, as can best be seen in FIG. 2, the rod is pushed along the handle 16 through the brackets 26 so that the tapered or pointed end 18a of the rod 18 is forced into the barbed wire reel. This positioning of the rod 18 prevents rotation of the barbed wire reel and the wheels 12 thereby creating tension or tightening of the strand 36 when tension or force is applied to the device 10 in a direction away from the point of connection of the barbed wire strand 36 on the fence.

The brake means or rod 18 is easily and simply operated. The handle portion 18c is turned from the downward position illustrated in FIG. 1 to the upward position as best seen in FIG. 2, and by pushing on the portion 18c the rod 18 is forced into contact with the reel of barbed wire thus preventing rotation of the barbed wire reel on the axle 14. The brake 18 is quickly and easily released by pulling on the portion 18c thus disengaging the rod 18 from the barbed wire reel.

The foregoing disclosure and description of the invention is illustrative and explanatory thereof. Various changes in the size, shape and materials, as well as in the

details of the illustrated construction, may be made within the scope of the appended claim without departing from the spirit of the invention.

Broadly the invention relates to a simple and economical device for stringing barbed wire fences.

What is claimed is:

A barbed wire reel holder including a pair of wheels each having an opening therethrough, a continuous axle extending through the opening in each of said wheels, the diameter of the openings in said wheels being larger than the external diameter of said axle, the external diameter of said axle being smaller than the internal diameter of the reel of barbed wire whereby the reel may be received thereon, adjustable means on said axle for retaining said wheels on said axle and for varying the distance between said wheels thereby permitting said reel holder to receive reels of various widths, a handle releasably connected to said axle for moving the holder and barbed wire reel supported thereon, said releasable connection including means on said handle for connecting said handle to said axle, a rod extending longitudinally on said handle, brackets on said handle for supporting said rod whereby said rod may be moved longitudinally along said handle, said rod having a tapered end thereon whereby said tapered end may be engaged with the barbed wire of the barbed wire reel to inhibit rotation of the reel on said axle, a rest arm attached to said handle for supporting said handle at a predetermined height, said rest arm being hingedly connected to the underside of said handle and positioned nonperpendicularly with the ground when in use, and clamp means for locking said rest arm adjacent said handle when not in use.
